UNITED STATES PATENT OFFICE.

CLARENCE LEE BURGES, OF WORCESTER, MASSACHUSETTS.

COLLAR-CREASING MACHINE.

SPECIFICATION forming part of Letters Patent No. 557,766, dated April 7, 1896.

Application filed October 26, 1895. Serial No. 566,940. (No model.)

To all whom it may concern:

Be it known that I, CLARENCE LEE BURGES, a citizen of the United States, residing at Worcester, in the county of Worcester and 5 State of Massachusetts, have invented a new and useful Improvement in Collar-Creasing Machines, of which the following is a specification.

The object of my invention is to provide 10 a strong, simple, and efficient machine for creasing collars.

To these ends my invention consists of the parts and combinations of parts, as herein-after described, and more particularly pointed 15 out in the claims at the end of this specification.

In the accompanying drawings, Figure 1 is a front view of a collar-creasing machine constructed according to my invention. Fig. 2 20 is a transverse sectional view of the same, and Figs. 3 and 4 are detail views illustrating the operation of the device.

A collar-creasing machine constructed according to my invention comprises a grooved 25 creasing-roller and a disk secured upon parallel shafts, which are so mounted in the framework of the machine that they can be moved into and out of engagement.

Referring to the drawings in detail, 30 designates a suitable pedestal or support. Fastened upon and carried by the pedestal 10 is a bed-piece or casting 11. Journaled in the bed-piece 11 is a driven shaft 12, carrying a pulley 13, a pinion or gear-wheel 14, 35 and a grooved creasing-roller 15. The grooved roller 15 is cored out or made hollow to coöperate with a burner or jet-pipe 16. The burner 16 is supplied with a mixture of air and gas by means of the pipes 17 and 18, which are 40 controlled by means of suitable valves, as shown. Projecting from the front face and preferably formed integrally with the grooved roller 15 is a bending section or roller 19. Mounted in the bed-piece 11 and arranged to 45 move in suitable guideways is a vertically-movable box 20. Journaled in the vertically-movable box 20 is a shaft 21, carrying a gear 22, which is adapted to mesh with and engage the pinion or gear 14, and a creasing- 50 disk 23, which is adapted to fit into and engage the grooved roller 15. A bolt 24, thread-

ed into the frame of the machine, is provided with a check-nut 25 and forms an adjustable stop to limit the upward movement of the box 20. A feed-roller 26 is journaled on an 55 extending arm in position to coöperate with the creasing-disk 23 when the same is moved to its highest position. The feed-roller 26 is preferably covered with felt or other flexible material. The vertically-movable box 20 and 60 the parts carried thereby are normally held in their lowest position by means of a spring 27, mounted on a vertical rod 28. The rod 28 is connected at its lower end to a treadle 29, which may be arranged or mounted in 65 any desired manner.

The operation of my improved collar-creasing machine as thus constructed is most clearly illustrated in Figs. 3 and 4. A collar which is to be folded or creased is placed in 70 position upon the disk 23, and the treadle is operated to bring the creasing-disk 23 and roller 15 into engagement and the gears 22 and 14 into engagement. The collar will then be fed forward by the action of the creasing 75 disk and roller and by the supplemental action of the feed-roller 26, so as to be properly creased or turned down. It is to be noted that the grooved roller 15 is considerably larger as compared with the disk 23 than the 80 gear or pinion 14 as compared with the gear 22. By means of this arrangement the peripheral speed of the grooved roller 15 will be considerably greater than that of its coöperating disk 23. I have found that this is an im- 85 portant point in practice, as the grooved roller 15, which acts upon the exterior surface of the collar, will have a certain slip or drag over the surface of the collar and will impart a de- 90 sirable polish or finish to the same. The pres- 95 sure exerted between the creasing disk and roller can be accurately regulated by means of the adjustable stop 24 and its check-nut 25. After a collar has been passed between the creasing disk and roller it can be bent to 100 the desired curvature by wrapping the same around the bending roll or section 19, as illus- trated in Fig. 4. One especial advantage in constructing my collar-creasing machine so that the creasing disk and roller are normally 100 out of engagement resides in the fact that by adopting this arrangement my machine may

be used for creasing what are known as "rolled-front" collars. In this class of collars only the middle or rear section of the collar is brought to a sharp crease. When a collar of this class is to be creased or finished, the collar is inserted some distance between the creasing disk and roller before the same are brought into engagement, and the disk and roller are separated before the end of the 10 collar is reached, thus preserving the rounded-over effect which is desired in this class of work. By using a tapered disk 23, as shown in the drawings, the work can be nicely laid in position thereon, and there is very little 15 danger of the hands of the operator being caught between the creasing-surfaces.

The machine constructed according to my invention may be employed for turning down the points of standing collars and for other 20 purposes which will be obvious to those who are familiar with the ordinary forms of laundry-work and need not be herein set forth at length.

I am aware that changes may be made in 25 the construction of the machine by those who are skilled in the art and that certain features may be used in different locations and in different combinations without departing from the scope of my invention as expressed 30 in the claims. I do not wish, therefore, to be

limited to the construction which I have shown and described; but

What I do claim, and desire to secure by Letters Patent of the United States, is—

1. In a collar-creasing machine, the combination of a bed-piece, a driven shaft 12 journaled in said bed-piece, a gear and grooved roller secured upon said shaft, said grooved roller being cored out or made hollow, an exterior heating device, as 16, a vertically-mov- 35 able box mounted in suitable ways in said bed-piece, a shaft 21 journaled in said box, a gear and creasing-disk secured upon said shaft, and a treadle for moving the shaft to bring the gears and creasing disk and roller 40 into engagement, substantially as described. 45

2. The combination of the creasing roller and disk, means for bringing said disk and roller into and out of engagement, and a supplemental feed-roller journaled upon a vertical axis in position to coöperate with the disk, 50 substantially as described.

In testimony whereof I have hereunto set my hand in the presence of two subscribing witnesses.

CLARENCE LEE BURGES.
